1,265,384.

Specification of Letters Patent.

Patented May 7, 1918.

Application filed April 12, 1917. Serial No. 161,396.

To all whom it may concern:

Be it known that we, GODFREY R. REBMANN, a citizen of the United States, residing in Philadelphia, in the county of Philadelphia and State of Pennsylvania, and WILLIAM H. HULTGREN, a citizen of the United States, residing in Roselle Park, in the county of Essex and State of New Jersey, have invented a new and useful Improvement in Chairs, of which the following is a specification.

Our invention relates to an improvement in chairs of the type used by dentists, barbers, surgeons, etc., and involves the use of fluid actuated by compressed air or other pressure supply, for elevating and lowering the seat of the chair.

More particularly, the invention involves a chair, the seat of which is supported by two telescoping plungers, the latter being mounted for operation within a casting forming the base or pedestal for the chair, and a reservoir containing an operating fluid, by means of which the plungers are operated, to move the chair seat up and down as desired. The operating fluid, which is preferably oil, is actuated by compressed air, the fluid and air being controlled by two valves operated by either one of two pedals, the latter being so constructed and arranged, relative to the valves and to each other, that depression of one of the pedals will cause the seat of the chair to move upwardly, and depression of the other will cause it to move downwardly. With no pressure on either pedal the chair will remain stationary. We have also provided interlocking mechanism for the pedals to prevent their simultaneous operation.

We have provided also a brake or holding device for the chair, to control its horizontal rotation, this brake being controlled by the pedals and operated by a light pressure on either of them, the valves being constructed so as to permit this slight depression of the pedals, without, however, causing the chair to be moved either up or down.

We have provided means by which the chair seat when nearing either limit of its vertical travel, will be brought to rest gradually and without appreciable shock or jar.

In the drawings accompanying this application, Figure 1 is a sectional elevation of

the base or pedestal of the chair; Fig. 2 is 55 a sectional elevation view of the air valve; Fig. 3 is a sectional elevation of the mechanism connecting the pedals with the fluid and air valves, and shows also in part section, the brake or holding device; Fig. 4 is 60 a part sectional elevation of the apparatus of Fig. 3, this view being taken at right angles to Fig. 3; Fig. 5 is a general arrangement view showing the pedal mechanism in plan connected to the fluid and air valves; 65 and Fig. 6 is a section taken through the base of the chair, showing the air valve in section.

Like characters of reference designate 70 like parts in the various figures.

Referring to the drawings in detail, and particularly to Fig. 1, a casting forming the base for the chair is designated 1, and 2 designates the platen to which the seat of the chair is attached, and which is mounted on 75 the top of a hollow plunger 3. The lower end of this plunger is provided with a plug 4 screwed thereinto. Screwed into the plug 4 and entering the plunger 3 is a member 5, to hold packing 6 in position between the 80 member 5 and the plug 4. Extending through the platen 2 is a rod 7, the lower end of which enters the member 5, to form a needle valve, the purpose of which will be pointed out hereinafter. The plunger 3 85 extends into and is keyed to a hollow plunger 8, the latter being mounted to move in a cylinder 9 provided in the pedestal or base 1. The lower end of the plunger 8, carries 90 a member 10 screwed thereinto, and constituting in conjunction with packing 11 a bearing against the cylinder 9. The member 10 has a projection 12, extending downwardly into a passage 13, communicating with a reservoir 19, by way of a valve chamber 95 and passage 47.

The air valve mechanism shown in Fig. 2, comprises a casing 14, within which is a rod 15, mounted for vertical movement therein. Carried on this rod is a valve 16, 100 adapted to be moved by the rod to open and close a port 18 leading to the reservoir 19. An exhaust port 17 is provided in the casing 14, this port leading to the atmosphere. The valve 16 is self-adjusting, in that it is 105 constructed to have lateral movement on the rod 15, being pressed firmly against its seat by the air under pressure, which is ad-

mitted to the casing 14 by way of a pipe 20, which may be connected to any suitable source of pressure supply.

The fluid valve 23, shown in Fig. 1, comprises a stuffing box 21, through which passes the rod 22, connected to the hinged slide valve 23, this valve controlling the passage of fluid to and from the reservoir 19.

10 The brake or holding device, which we have provided to control the rotation of the chair seat about its vertical axis, comprises, as will be seen from Figs. 1 and 3, a bell crank lever 24, engaging at its upper end a member 25, which in turn engages a brake shoe 25' partially surrounding the plunger 8. The member 25 is provided for the purpose of preventing wear on the end of the lever 24, which would occur should the lever 20 engage the brake shoe 25' directly. The other end of this lever is connected by a nut 26, and a link 27 screwed thereinto, and a member 28, to a rod 29, the latter being adapted to slide in a guide 30 attached to 25 the pedestal 1. The nut 26 which is pivoted to the lower end of the lever 24, and the threaded member 27, are provided for the purpose of adjusting the brake pressure on the plunger 8, and also to take up such lost 30 motion as may develop by reason of the wear of the brake member 25' and contiguous parts.

The mechanism for operating the fluid and air valves, and the brake device, will 35 now be described, this mechanism being best illustrated in Figs. 3, 4 and 5. The rod 22 to which the fluid valve 23 is pivotally connected, is attached to a crosshead 32, this crosshead being mounted for vertical movement upon a guide rod 33, the latter being held in position in a guide casting 36. The other end of the crosshead 32 is connected to the rod 15 carrying the air valve 16. The rod 33 extends through the cross head 32, 45 down through sleeves 37, 37, and a spring 34, and is free to be moved vertically, a head 35, being provided on its lower end, this head engaging the lower sleeve 37, as viewed in Fig. 3. The crosshead engages the upper sleeve 37 as viewed also in Fig. 3, so that normally the rod 33 and therefore the crosshead 32 will be in the position shown in Fig. 3, being held in such position by the action of the spring 34.

50 55 Connected to the crosshead 32 by means of a link 38, are pedals 39 and 40. The pedal 40 carries an arm or lever 41, connected to the link 38, and the pedal 39, carries a similar arm or lever 42, operating upon the lever 41 by means of a pin 43. The pin 43 is rigidly connected to the lever 41, its other end entering a squared bushing 43', carried in a slot in the lever 42, and adapted to have a slight longitudinal movement therein. 60 65 Pressure on the pedal 40, will, by means of

the lever 41 and link 38, compress the spring 34, and move the crosshead 32 upwardly. So soon as the pedal is released, the parts will assume the position shown in Fig. 3, by reason of the spring 34. Pressure on the 70 pedal 39 will compress the spring 34 and move the crosshead 32, by means of the lever 42, pin 43, lever 41, and link 38, in the opposite direction to which it was moved when the pedal 40 was operated. As before, 75 the parts will return to normal position when pressure on the pedal 39 is removed. Inasmuch as the rod 29 of the brake device is connected to the cross head 32, as shown in Fig. 3, it will be seen that operation of 80 either pedal will release the brake, to allow the chair to be rotated about its vertical axis. By means of the interlocking of the pedals through the levers 41 and 42 and the pin 43 and bushing 43', should the attendant inadvertently attempt to operate both pedals simultaneously, they will remain stationary. 85 with the member 32 in its normal position.

The cylinder 9 outside of the plunger 8 is filled with a fluid, and the reservoir 19 and 90 the plunger 3 are partially filled with the same fluid. Oil is preferably used, as this keeps all the parts well lubricated, eliminating wear.

With the chair in the position shown in Fig. 95 1, the attendant depresses the pedal 40, which will actuate the valve 23, through the mechanism already described, to open the passage 13, communicating with the reservoir 19 by way of port 47, and at the same time the air valve 16 will be actuated to admit air under pressure, by way of the pipe 20 and port 18, to the passage 50 communicating with the reservoir 19, over the top of the fluid in said reservoir. So soon as the 100 pressure within the reservoir has risen sufficiently to overcome the inertia of the plungers 3 and 8, and their load, the fluid will cause the plungers to move upwardly, the upward movement of the plunger 8, gradually displacing the fluid in the cylinder 9, and forcing the same through the ports 45 and 46 provided in the walls of the plunger 8, to the space beneath the plunger 3, to cause the latter to move upwardly relatively 105 to the plunger 8. If the pedal 40 is now released, the valve 23 will be returned by the spring 34 to the position shown in Fig. 1, and the air valve to the position shown in Fig. 2, thus cutting off simultaneously, the 110 passage of fluid to the bottom of the plunger 8, and the admission of air to the top of the fluid in the reservoir 19. The chair will now be held stationary. Should there be any 115 leakage of air from the reservoir 19, and a consequent drop in pressure in the said reservoir, the fluid under the plungers will tend to flow back to the reservoir 19, due to the weight of the plungers and their load, but this will cause the valve 23 to be rotated 120 125 130

about its pivot to close off the port 47 and thus prevent any discharge of fluid from beneath the plungers; the chair therefore will remain in its elevated position.

5 Assuming now that it is desired to elevate the chair still farther, the pedal 40 may be again depressed, opening the air valve to admit pressure to the top of the fluid in the reservoir 19, as before, but should at this 10 time the pressure not be sufficient to cause the plungers to be moved upwardly, they will still remain stationary until the pressure has risen sufficiently, for the reason that the valve 23 will have closed off the port 47, and 15 will keep it closed off until such time as the pressure in the reservoir 19 has overcome the pressure on the fluid due to the plungers and their load, when it will rotate on its pivot, uncovering the port 47, and allow fluid 20 to flow beneath the plungers to elevate them still farther.

Should the attendant neglect to remove his foot from the pedal 40, the plungers 8 and 3 will nevertheless come to rest automatically and without shock or jar, by reason of the fact that as the plunger 8 approaches its upper limit of movement, it gradually closes off the ports 45 and 46, thereby cutting off the circulation of fluid 30 from the cylinder 9, which is acting upon the plunger 3, and the plunger 8 will be prevented from moving upwardly any farther, by the member 10 carried at the bottom of said plunger seating against the shoulder 45 48 provided at the top of the cylinder 9.

To lower the chair, the attendant depresses the pedal 39, to actuate the cross-head 32 downwardly as viewed in Fig. 4, moving the valves 23 and 16 into position 40 to permit the discharge of fluid from beneath the plungers 3 and 8, that beneath the plunger 8 flowing by way of passage 13 back to the reservoir 19, and that beneath the plunger 3 flowing back into the cylinder 9 45 as the plunger 8 moves downwardly, the air exhausting from the reservoir 19 by way of passage 50, and ports 18 and 17 to the atmosphere. As the plunger 8 nears its lower limit of travel, the projection 12 on the member 10, by entering the passage 13 gradually cuts off the passage of fluid from beneath the plunger and the plunger will come to rest gently and easily, with the projection 12 resting on the boss 51 formed in the bottom 55 of the passage 13, as shown in Fig. 1.

With a load on the chair, with the chair in elevated position, the fluid in the reservoir 19, is under a pressure depending upon the weight of the chair and its load, and 60 should the chair have been brought to rest on its up motion, the valve 23 will be in the position shown in Fig. 1. If the load on the chair were now removed, the chair will remain in the same position, although the pressure 65 in the reservoir would tend to force the

fluid therein in a direction to flow beneath the plunger 8, but this flow is prevented by the valve 23, which has closed the passage 13, and the pressure from the reservoir 19 will merely press the valve more firmly 70 against its seat to maintain the said passage closed. Or should the valve 23 be in position to close off the port 47, due to leakage of air from the reservoir 19, with the chair at rest, or due to the fact that the chair was stopped 75 on the down motion, leaving the passage 13 open, the pressure from the reservoir 19 if it exceeds the pressure on the fluid due to the weight of the chair with the load off, would at once cause the valve 23 to rotate on its 80 pivot and immediately close off the passage 13. If the pressure on the fluid due to the weight of the chair is higher than the pressure in the reservoir 19, the valve will be merely held more firmly seated to close off 85 the port 47. Also it is to be noted that should a person of comparatively light weight seated in the chair, be replaced by one of heavier weight, the extra load on the chair will not cause the chair to settle, for 90 the valve 23 would at once close off the port 47 and prevent any flow of fluid back to the reservoir 19.

It will be seen from Figs. 1 and 2, that, we have provided the valves 23 and 16 with 95 sufficient lap to permit the pedals 39 and 40 to be operated to actuate the brake mechanism, without, however, actuating the valves sufficiently to uncover the ports controlled thereby.

Any air which may find its way to the cylinder 9 may be exhausted therefrom, by merely unscrewing the rod 7 slightly, and raising the plungers 3 and 8 by hand, and then allowing them to settle back into place 105 by their own weight; the fluid in the plunger 3 will flow into the cylinder 9 and fill it up, and the air will be forced out and through the fluid in the plunger 3, where it may escape to the atmosphere between the 110 rod 7 and the seat of the chair.

It will be seen from the foregoing, that we have provided an apparatus of the class described, which is simple in construction, positive in action, and which to be operated 115 requires practically no exertion on the part of the operator.

We have shown and described one embodiment of our invention, but we appreciate that others skilled in the art might make 120 various changes in the details of construction and arrangement of parts herein shown, without departing from the spirit and scope of our invention. We desire, therefore, not to be limited to the precise details of construction and arrangement of parts shown, but what we claim as new, and desire to secure by Letters Patent of the United States is:—

1. In an adjustable chair, supporting 130

means for the seat of the chair, a fluid chamber, a pressure supply for placing under pressure a fluid in said chamber, to actuate the seat-supporting means, ports for the passage of fluid to and from said fluid chamber, and a slide valve automatically controlling said ports.

2. In an adjustable chair, supporting means for the seat of the chair, a fluid chamber, a pressure supply for placing under pressure a fluid in said chamber to actuate the seat-supporting means, pressure supply and discharge ports, and a slide valve automatically controlling the flow of fluid through said ports alternately for pressure or discharge.

3. In an adjustable chair, supporting means for the seat of the chair, a fluid chamber, a pressure supply for placing a fluid under pressure in said chamber to actuate the seat-supporting means, ports for the passage of the fluid to and from the fluid chamber, a slide valve for controlling said ports, operating means therefor, and means cooperating with said valve whereby the latter will automatically close off either of said ports without actuation of the said operating means.

4. In an adjustable chair, supporting means for the seat of the chair, a fluid chamber, a pressure supply for placing a fluid under pressure in said chamber to actuate the seat supporting means, ports for the passage of the fluid to and from the fluid chamber, a slide valve for controlling said ports, operating means therefor for adjusting the chair-seat-supporting-means, said valve operating automatically under the action of the fluid to close off either of said ports without actuation of the valve operating means.

5. In an adjustable chair, supporting means for the seat of the chair, a fluid chamber, a pressure supply to generate pressure upon the fluid in said fluid chamber to adjust the chair seat supporting means, a self-adjusting valve for the application of pressure from the pressure supply, and the exhaust of pressure to the atmosphere, a hinged slide valve actuated in part by the direction of flow of the fluid to and from the pressure chamber to automatically maintain the chair seat in any elevated position should a reduction or variation of pressure from any cause occur at the source of pressure supply.

6. In an adjustable chair, plungers supporting the seat of the chair, a fluid chamber, a cylinder within which said plungers may be moved, a pressure-regulating self-adjusting valve, a pressure supply controlled thereby, said valve being placed between the source of pressure supply and the fluid chamber, a hinged slide valve between the fluid chamber and the plunger cylinder, and interlocking pedals connected to the valves

mechanically, by which manipulation of said pedals positively predetermines the direction of motion of the said plungers and therefore of the chair seat.

7. In an adjustable chair, plungers supporting the seat of the chair, a fluid chamber, a pressure supply for placing a fluid in said chamber under pressure to actuate the chair-seat supporting means, valves controlling the pressure supply and the flow of fluid under the action of the pressure supply, a brake to prevent horizontal rotation of one of the plungers, interlocking pedals having operating connections to the valves and the brake, and means for automatically returning the valves and brake to normal position by release of pressure from either one of the interlocking pedals.

8. In an adjustable chair, supporting means for the seat of the chair, a fluid chamber, a pressure supply for placing a fluid in said chamber under pressure to adjust the chair-seat supporting-means, a brake for the chair-seat supporting-means, a self adjusting valve controlling and regulating the pressure supply, a slide valve actuated in part automatically by the direction of flow of fluid for controlling said fluid, interlocking pedals for controlling said valves and brake, and a compression spring guided in cup sleeves and reacting alternately for up or down motion, for returning automatically the entire operating mechanism to normal position by which all pressure actuated parts are brought to rest upon release of pressure from either one of the interlocking pedals.

9. In an adjustable chair, plungers supporting the seat of the chair, a fluid chamber, a pressure supply for actuating a fluid in said chamber to adjust the plungers, a self-adjusting valve controlling said pressure supply, a slide valve controlling the flow of the fluid under pressure and actuated in part automatically by the direction of flow of the fluid, a brake for preventing rotation of one of the said plungers which is adapted to be rotated by hand, interlocking pedals controlling said brake and valves, ports arranged to automatically limit the axial movement of the plungers under the action of the fluid under pressure, a valve within the rotatable plunger for facilitating discharge of air which would prevent action of the pressure actuated parts, and also to facilitate replenishment of such fluid as may escape by reason of leakage, and means for effecting the automatic return to normal position of the operating parts of the mechanism, by which the telescopic plungers and pressure actuated parts are brought to rest upon release of pressure from either one of the said pedals.

10. In an adjustable chair, supporting means for the seat of the chair, a fluid chamber, a pressure supply for placing the fluid

in said chamber under pressure to actuate the seat supporting means, hinged slide valve mechanism controlling the supply and exhaust of fluid to and from said supporting means and operating automatically to maintain the chair seat in elevated position should the pressure on the fluid due to the weight of the supporting means and its load exceed that due to the pressure supply.

- 10 11. In an adjustable chair, the combination with a fluid chamber, supporting means for the seat of the chair, a pressure supply for actuating the fluid in said chamber to actuate the supporting means, ports controlling the passage of fluid to said supporting means, a hinged slide valve controlling said ports and operating automatically by the pressure in the fluid to maintain the supporting means in adjusted position.
- 15 12. In an adjustable chair, supporting means for the seat of the chair, a fluid chamber, a pressure supply for placing the fluid under pressure in said chamber to actuate the seat supporting means, ports for the 20 passage of fluid to and from the fluid chamber, and hinged slide valve mechanism controlling the said ports.

13. In an adjustable chair, supporting means for the seat of the chair, a fluid chamber, a pressure supply for placing the fluid in said chamber under pressure to actuate said supporting means, hinged slide valve mechanism controlling the supply and exhaust of fluid to and from said chamber, 25 said valve mechanism adapted to be operated by the pressure on the fluid to maintain the chair stationary.

14. In an adjustable chair, supporting means for the seat of the chair, a pressure supply for placing a fluid in said chair under pressure to actuate said supporting means, a valve for controlling the pressure supply, a valve for controlling the passage of fluid actuated by the pressure supply, 30 single means for actuating said valves simultaneously, and means for automatically restoring the valves to closed position, one of said valves when not actuated by the said single actuating means operating automatically to maintain the chair seat supporting means stationary.

15. In an adjustable chair, supporting means for the seat of the chair, a pressure supply for placing the fluid in said chamber under pressure to actuate said supporting means, valve mechanism for controlling the pressure supply and the passage of fluid actuated thereby, a single device for actuating said valve mechanism to elevate the chair, a single device for actuating said valve mechanism to lower the chair, and means for preventing the simultaneous operation of said single devices.

16. In an adjustable chair, the combination of supporting means for the seat of the

chair, a fluid chamber, a pressure supply for placing the fluid under pressure in said chamber to actuate said supporting means, valve mechanisms for controlling the pressure supply and the passage of fluid actuated thereby, single means for actuating said valve mechanisms simultaneously to cause the chair seat supporting means to be elevated, a single means for actuating the valve mechanisms simultaneously to lower 70 the chair seat supporting means, and means operating automatically to always restore the valve mechanisms to position to maintain the chair seat supporting means in any desired position, said valves operating automatically to prevent movement of the chair seat supporting means in an ascending direction except the pressure in the fluid due to the pressure supply exceeds that due to the weight of the chair seat supporting 75 means and its load.

17. In an adjustable chair, supporting means for the seat of the chair, a fluid chamber, a pressure supply for placing the fluid under pressure in said chamber to actuate said supporting means, valve mechanism for controlling the pressure supply and the passage of fluid actuated thereby, means for actuating said valve mechanism, mechanism for controlling the horizontal 90 rotation of the chair seat, and a device for actuating said valve mechanism, a partial movement of which in the direction for actuating the valve mechanism will operate the mechanism for controlling the horizontal 95 rotation of the chair seat without actuating the valve mechanism to operative 100 position.

18. In an adjustable chair, the combination with a fluid chamber, supporting 105 means for the seat of the chair, a pressure supply for forcing fluid from said chamber beneath the supporting means, a hinged slide valve controlling the passage of fluid to and from said fluid chamber, and adapted 110 to automatically prevent the passage of fluid beneath the supporting means should the pressure on the fluid due to the weight of the supporting means and its load be less than the pressure on the fluid due to the 115 pressure supply.

19. In an adjustable chair, the combination with a fluid chamber, supporting means for the seat of the chair, a pressure supply for forcing fluid from said chamber beneath the supporting means, ports controlling the passage of fluid to and from said fluid chamber, a hinged slide valve controlling said ports, and adapted to automatically prevent the flow of fluid back to the 120 fluid chamber should the pressure in the fluid chamber due to the pressure supply be lower than that on the fluid due to the weight of the supporting means and its load.

20. In an adjustable chair, the combina- 130

- tion of a fluid chamber, supporting means for the seat of the chair, a pressure supply for forcing fluid from said chair beneath the supporting means, a hinged slide valve 5 controlling the passage of fluid to and from said fluid chamber, and adapted to automatically prevent the passage of fluid to the supporting means should the pressure on the fluid due to the weight of the supporting 10 means and its load be less than the pressure on the fluid due to the pressure supply.
21. In an adjustable chair, the combination with a fluid chamber, of supporting means for the seat of the chair, a pressure supply for actuating said fluid to actuate the supporting means, a valve controlling the fluid, a valve controlling the pressure supply, means for operating said valve simultaneously, and a spring compressed by 15 movement of the valves to raise or lower 20 the supporting means to restore the valves to closed position to bring the supporting means to rest, the fluid valve operating automatically to maintain the chair seat supporting-means stationary. 25
22. In an adjustable chair, a fluid chamber, a pressure supply for placing a fluid in said chamber under pressure to elevate the chair seat, and a hinged slide valve controlled by the pressure in the fluid for automatically maintaining the chair seat in elevated position. 30
23. In an adjustable chair, a fluid chamber, hollow plungers therein forming a support for the seat of the chair, valve mechanism in one of said plungers for replenishing the fluid in said chamber with fluid from said plunger. 35

In testimony whereof, we have signed our names to this specification.

GODFREY R. REBMANN.
WILLIAM H. HULTGREN.
